DESIGN FOR A BUILDING

Peter Copeland, New York, N. Y., assignor to Ben Wolfman, Inc., Houston, Tex., a corporation of Texas

Application April 16, 1947, Serial No. 138,433

Term of patent 14 years

(Cl. D13—1)

To all whom it may concern:

Be it known that I, Peter Copeland, a citizen of the United States, residing in New York, county of New York, and State of New York, have invented a new, original and ornamental Design for a Building, of which the following is a specification, reference being had to the accompanying drawing forming a part thereof.

The figure is a front perspective view of a building, showing my new design.

I claim:

The ornamental design for a building, as shown.
PETER COPELAND.
